UNITED STATES PATENT OFFICE.

LYNN GRAY, OF WAUPUN, WISCONSIN, ASSIGNOR, BY MESNE ASSIGNMENTS, TO PARAMOUNT TEXTILE MACHINERY CO., OF CHICAGO, ILLINOIS, A CORPORATION OF ILLINOIS.

HOSIERY DRYING AND SHAPING FORM.

Application filed March 24, 1921. Serial No. 455,088.

To all whom it may concern:

Be it known that I, LYNN GRAY, a citizen of the United States, residing at Waupun, in the county of Dodge and State of Wisconsin, have invented certain new and useful Improvements in Hosiery Drying and Shaping Forms, of which the following is a specification, reference being had therein to the accompanying drawing.

10 This invention relates, broadly, to hosiery finishing apparatus and, more especially, to structures for drying and shaping so-called "full-fashioned" and "mock-seam" hosiery.

As distinguished from so-called "seamless" 15 hosiery, full-fashioned hosiery is of a type that is knit in sheet form and then has its longitudinal edges sewed together. When this is done, a seam extending from the toe to the top of the stocking is produced.

20 "Mock-seam" hosiery is knit in tubular form, and it really is seamless; but a longitudinal seam is simulated in the fabric so that the article shall resemble full-fashioned hosiery.

25 In the "boarding" of both full-fashioned and mock-seam hosiery, the practice with some manufacturers is to lay the seam or mock-seam somewhat to one side of the longitudinal line, this resulting in the produc-

30 tion of what are called "rights" and "lefts", this name arising from the fact that the seam would, by the boarding, be disposed to the right or to the left of the longitudinal line. With other manufacturers, the practice is to lay the seam along said longitudinal line and, thus, avoid the production of rights and lefts; and, for that practice, the hosiery finishing forms disclosed in Letters-Patent No. 1,218,520, granted March 6, 1917,

35 and No. 1,268,066, granted May 28, 1918, may be efficiently utilized.

In Patent No. 1,075,346, granted October 14, 1913, there is disclosed a hosiery finishing board adapted for the "boarding" of full-fashioned hosiery to produce rights and lefts:

40 The board, in this patent, consists of a metal sheet cut to the shape of a stocking and provided at one edge with a groove which is located a distance from the rear edge of the finishing board and extending from the top of the leg around the heel-portion of the board and terminating at the toe-end thereof. The sole purpose of the groove, in this instance, is to receive the

seam of the hosiery and prevent the latter 55 from shifting while the stocking is shrinking during the finishing process.

As a result of considerable experimentation with a drying and shaping form provided with a longitudinal groove that receives and holds the seam from shifting, I have discovered that it presents certain difficulties and disadvantages which it is the object of the present invention to overcome.

Where relatively large production in a mill 60 is a desideratum, it is found that it requires considerable skill and time to dispose the seam in the groove in the form mentioned

and, besides, the finished product is not altogether satisfactory; whereas, with a drying 65 and shaping form made in accordance with my invention, a very satisfactory product is possible without at all slowing down

70 production: This result is made possible by making the edge of the form of quite a different character, such that an incut or channel formed with approximately right-angled walls or surfaces is presented, each of these

75 walls being adapted to function in a manner presently to be explained and, thus, operating in a way different from the grooves 80 in the forms disclosed in any of the three aforementioned patents.

The structure of my invention is characterized by having its front and rear portions 85 provided with crease-producing edges, there being associated with the rear edge an incut or channel having right-angular walls, one of the walls terminating in the crease-producing edge whereby a crease in the hosiery will be produced in close proximity to the seam, and the seam, itself, be so disposed in the resulting product in relation to the crease that it shall have the appearance 90 of being flattened out. The foregoing statement relates, of course, to full-fashioned

95 hosiery.

100 Where mock-seam hosiery is treated on such a form, the simulated seam is disposed in the same relation to the crease, the incut or right-angular channel enabling the lining up of the mock-seam in a straight longitudinal line to produce a product having a high class and finished appearance.

105 In order that my invention may be more readily comprehended, I have illustrated three embodiments thereof which, in actual practice, have been found to be highly effi-

cient. In thus illustrating these three embodiments, it is to be understood that my invention is not restricted thereto, and that the invention is susceptible of considerable modification without departure from its underlying principles and salient features and advantages.

In these drawings:

Figure 1 is a view in perspective of an internally heated hosiery drying and shaping form with a full-fashioned stocking superposed thereon, a portion of the latter being cut away to disclose, first, the seam-receiving incut or channel of the form, and, also, the relation thereto of the seam in the goods;

Fig. 2 is a view in transverse section on the line 2—2, Fig. 1;

Fig. 3 is a fragmentary view, in section, on a much larger scale, and showing more particularly the shape of the incut or channel in the form and the manner in which the seam is disposed therein and in relation to the crease formed in the goods adjacent the seam;

Fig. 4 is a view similar to Fig. 2, but showing a modified type of form particularly useful for finishing mock-seam hosiery, the seam-receiving incut in this instance being (for illustration purposes only) disposed on the side of the crease-producing edge opposite to that shown in Fig. 2, and extending from near the base of the form to the heel-portion thereof;

Fig. 5 is a view similar to Fig. 3 showing the mock-seam of the hosiery in its relation to the incut in the form; and

Fig. 6 is a fragmentary view of another modification, in which seam-seating incuts are provided on both sides of the form.

Referring to these drawings, and to Figs. 1 to 3 thereof, the reference-numeral 1 indicates a stocking of the so-called full-fashioned type. This is shown as provided with a seam 2 at the rear and extending from the toe of the stocking to the top thereof.

In order that the full-fashioned type of hosiery may be efficiently finished—that is, simultaneously dried, creased, and shaped—

I preferably make the form 3 hollow to adapt it to contain a thermal fluid for heating it from within. By preference, this form has arc-shaped sides 4 and 5, these being shaped to present oppositely-bulged, fabric-flattening surfaces which converge and terminate in relatively reduced crease-producing edges 6 and 7, these sides and edges having the function of simultaneously creasing, shaping and finishing the front and rear portions, as well as the sides, of the stocking.

Adjacent the rear crease-producing edge of the form 6 is an elongated incut or channel 8, preferably extending from near the base 9 of the form to the toe-end 10 thereof,

and formed in the side 4 and adjacent the crease-producing edge 6. The incut 8 comprises a lateral wall 11 and a longitudinal wall 12, the walls 11 and 12 being disposed in approximate right-angular relation, as shown particularly in Figs. 2 and 3. The wall 11 presents what I shall herein designate a seam-seating surface, while the wall 12 presents what I shall herein designate as a seam-abutment surface. The lateral wall 11 terminates in a corner 11^a which, preferably and as shown, is relatively sharp so as to constitute an effective instrumentality to engage and hold the seam from being twisted off the seam-seating surface 11. Similarly, the abutment-surface 12 terminates in a corner 12^a which likewise functions to prevent the seam from being dislocated out of the channel 8 when the fabric is moved in a clockwise direction, as viewed in Fig. 5, for instance.

When the stocking is being placed on the form, the seamed portion thereof will be placed so as to be disposed in relation to the incut 8; and, as the stocking is pulled down on the form and into its ultimate finishing position thereon, the seam will be lined up so that it will bear a particular relation to the entire length of the incut 8. In rapid work, the seam will not initially be disposed in exact line with the incut, and this fact necessitates a shifting of certain portions of the hosiery by the operator so as to bring the same in proper alignment and in a precise relation to the incut. The shifting of the hosiery is transverse to its length; and, under normal conditions, the aforementioned manipulation has a tendency to move the seam too far; but, in boarding with a form constructed in accordance with my invention, the abutment surface 12 acts not only as a guide to the operator but as an abutment for the seam to prevent its movement over the crease-producing edge 6. In other words, the wall 12, being angular both to the hosiery-engaging surface of the side 5 and to the wall 11, presents a sort of seam-engaging surface which holds the seam against undesirable movement that would otherwise throw it up onto or beyond the crease-producing edge 6.

When the seam has been brought into the aforementioned holding engagement with the abutment surface 12, any movement of the seam in the opposite direction, by reason of continued manipulation by the operator, will cause the seam to be brought into holding engagement with the angular wall 11 and this, then, constitutes an abutment for the seam against movement of the latter beyond the corner 13 formed at the edge of the form-wall 4. In consequence, the seam will be properly seated, first, against the wall 12, and, secondly, against the wall 11 and, as a result, will be exactly lined up

in the angular incut 8. The result is that the seam is disposed in an exactly straight line throughout the length of the stocking and at one side of the crease 14 formed in the hosiery adjacent the seam. Thus, it will be seen that I produce a product which is characterized by creases formed in its front and rear portions and with the seam thereof lined up in true relation to the crease 14 and at one side thereof, but in close proximity thereto.

Where mock-seam hosiery is being boarded on this type of form, the mock-seam 15—being of a character not unlike the seam in full-fashioned hosiery—is similarly caused to be lined up against the angular walls 12 and 13 of the incut 8 and with the crease 14 formed at one side thereof but in close relation thereto, as shown particularly in Fig. 5.

It will be understood that the incut 8 may be formed either in the form-wall 4, or in the form-wall 5, according to whether the form is to produce a "left" or "right" and the positions of these incuts, in opposite sides of the form 3, are illustrated in Figs. 1 to 5. Or, as shown in Fig. 6, there may be incuts 16 and 17 formed in both walls 4 and 5 so as to provide the angular surfaces 18—19 and 20—21 on opposite sides of the crease-producing edge 22. This type of form permits the boarding of either rights or lefts on the same form.

From the foregoing, it will be perceived that I have devised a novel hosiery-boarding form peculiarly adapted for the finishing of both full-fashioned and mock-seam hosiery. It is to be understood, however, that, by reason of the provision of the crease-producing edge 6 at the portion of the form where the incut 8 is disposed, I can satisfactorily board ordinary seamless hosiery on this type of form. In consequence, my improved type of form has advantages over those disclosed in the aforementioned Patents Nos. 1,218,520 and 1,268,066, because, with said patented forms, by reason of the fact that they have only one crease-producing edge as a feature of each form, seamless hosiery cannot satisfactorily be finished thereon. With the finishing board shown in Patent No. 1,075,346, this board is not adapted to be used for simultaneously drying and shaping hosiery—the expression, in this instance, including the idea of crease-producing.

It will be manifest that, as the hosiery is pulled onto the forms in a comparatively wet condition, and the forms being relatively hot, the moisture in the fabric will be evaporated and cause the fabric to become set or fixed. The hosiery, when placed on the forms, is stretched to the dimensions, approximately, of the ultimate product, and the evaporation of the moisture from the fabric produces this setting or fixing thereof and, simultaneously, the fixing of the

creases at its front and rear portions. At the same time, the relative position of the seam to the proximate crease is likewise fixed; so that the product is thereby given a "finished" appearance and made ready for the market without a subsequent finishing treatment.

What I claim is:

1. A drying and shaping structure for treating hosiery including a form provided with oppositely disposed crease-producing edges and with an L-shaped incut disposed adjacent one of the crease-producing edges, and comprising approximately right-angular, substantially flat walls to present angularly disposed surfaces including, respectively, a seam-seating surface and a seam-abutment surface extending in a plane approximately central of the form and terminating in a corner in substantial alinement with the crease-producing edge at the opposite portion of the form, and having the dual function of preventing dislocation of a seam of the stocking being boarded on the form and also of effecting a crease in the stocking adjacent its seam.

2. A drying and shaping structure for treating hosiery, including a hollow form to contain a thermal fluid and having curved fabric-flattening sides, and provided at its front and rear portions with crease-producing edges, and having in close proximity to one of the crease-producing edges an elongated, approximately L-shaped incut formed with a substantially flat seam-seating wall terminating in a relatively sharp corner to block the seam against movement beyond the wall in one direction, and with a substantially flat seam-abutment wall extending in a plane approximately central of the form and terminating in a relatively sharp corner to block the seam against movement beyond said wall and arranged in substantial alinement with the oppositely-disposed crease-producing edge, the curved fabric-flattening sides of the form extending from said corners.

3. A drying and shaping structure for drying and finishing full-fashioned or mock-seam hosiery comprising a hollow form containing a heating medium and having sides which converge to oppositely-disposed crease-forming edges to crease the front and rear of the goods, one of the sides being provided adjacent one of the crease-producing edges with an elongated approximately L-shaped incut having angular walls, each substantially flat, and both of which present two distinct surfaces, one being a seam-seating surface terminating in a relatively sharp corner to block the seam against movement beyond such wall in one direction, and the other wall constituting a seam-abutment surface and likewise terminating in a relatively sharp corner to block the seam against

movement beyond that wall in one direction and arranged in substantial alinement with the oppositely-disposed crease-forming edge of the form whereby the seam or mock-seam of the goods is lined up parallel to and in close relation to one of the creases formed in the goods, the crease formation in the goods and the position of the seam remaining fixed

by reason of the setting of the fabric due to the evaporation of the moisture therefrom produced by the heated form; the sides of the form extending from said corners and terminating in said oppositely-disposed crease-producing edges.

In testimony whereof I affix my signature.

LYNN GRAY.
